Application June 25, 1938, Serial No. 215,824

4 Claims. (Cl. 266—5)

This invention relates to a device for heat-treating a steel part or element. More particularly the invention relates to a device for electrically heat-treating an element by passing the same through at least a pair of spaced, 5 current-conducting members formed to engage the element and to heat-treat the same in accordance with the properties of the element and with the results desired; and, also to supply a quenching medium to the portion so treated at a point or points and within a space of time also in accordance with the properties of the element and the results desired.

The invention contemplates principally a means for electrically heat-treating an element in a desirable and efficient manner, preferably through the use of a pair of spaced, current-conducting rollers between the peripheries of which the element is passed in a linear path, the rollers being so formed as to concentrate current along a predetermined portion of the element. Each roller preferably employed in a suitable device is considerably large as compared to the thickness of the portion of the element to be treated thereby. Since the roller is large and has a considerable mass, it has a tendency, because of its inherent properties, to cool prematurely portions of the thickness of the element while excessively heating other portions.

Since the result of such treatment is undesirable, it is important, and a principal object of the invention, that the peripheries of the rollers be formed with current-concentrating portions.

Another object of the invention, and similarly important and desirable, is the provision of a plurality of heat-treating means in the form of units, each comprising a pair of spaced current-conducting members for heat-treating opposite portions of the element without increasing the number of steps in the operation.

Another important object is to provide a simple and efficient means for carrying the element in its path between the members.

Another object is to provide, when the element consists of a pair of opposite edges each of which is to be treated, heat-treating means at opposite sides of the carrying means and with respect to the portions of the elements to be treated in a manner providing for treatment of first one portion and then the other.

Another object is to provide for mounting the element on the carrying means movable within limits with respect thereto for changing the position of the element with respect to the positions of the heat-treating members.

Another object is to provide means for efficiently changing the position of the element as above.

Still another object is to provide means for supplying a quenching medium to the treated portions of the element substantially immediately after portions pass through and are treated by respective heat-treating members.

And still another object is to direct the flow of the quenching medium with respect to the portion treated.

Briefly and specifically, these and other desirable objects of the invention may be achieved by the device and in the manner chosen for the purposes of illustration, in which a steel part or element has a portion thereon of substantially uniform thickness, which is to be heat-treated along a certain width thereof. The element is mounted on a conveyer or carrying means which operates in a linear path alongside the faces of a pair of current-conducting members, such as rollers or the like. The peripheries of the rollers are formed with current-concentrating portions in the form of a plurality of spaced annular ribs. As the carrying means moves in its linear path, the portion on the element to be treated is passed between the peripheries of the rollers, and through the medium of the annular ribs current is concentrated throughout the portion to be treated in a manner achieving a uniform result. A quenching medium supply means in the form of a tube or pipe is located adjacent the rollers at the side thereof from which the element emerges. This pipe is provided with a slot substantially equal to the length of the portion of the element to be treated. As the element passes between the rollers, that portion thereof already heated is substantially immediately quenched by the flow of quenching medium through the slot in the pipe.

A further understanding of the objects, construction and important features of the invention will be had from the following detailed description, of a preferred device, taken in conjunction with the accompanying sheets of drawings illustrating the same.

In the drawings:

Figure 1 is a plan elevational view of a suitable device as referred to above;

Figure 2 is a side elevational view of the same with a portion of the supporting means for one pair of rollers omitted;

Figure 3 is an end elevational view in section of one of the supporting means for a pair of spaced current-conducting rollers, the view being taken substantially along the line 3—3 of Figure 1 and showing the position of the rollers with respect to the element to be treated;

Figure 4 is a somewhat reduced sectional view taken substantially on the line 4—4 of Figure 3, and showing the mounting of the bearing for the lower roller in the supporting structure;

Figure 5 is a front elevational view of one of

the supporting means with the current-conducting rollers removed;

Figure 6 is an enlarged longitudinal sectional view through the member for carrying the element to be treated; and,

Figure 7 is a transverse sectional view of the same showing the means for limiting the movement of the carrying member with respect to the carrying means.

10 The device embodied in the particular construction of the invention as illustrated in the drawings includes a base or table 10, on which is mounted a motive means, such as an electric motor 11, which is operatively connected through 15 reduction worm gearing, contained in the housing 12, to drive a shaft 13. The shaft 13 is rotatably supported in a pair of spaced brackets or bearings 14 rigidly secured to the base or table 10. The table 10 also has rigidly secured 20 thereto at a point spaced longitudinally from the bearings 14, a second pair of bearings or brackets 15, in which is rotatably carried a shaft 16. The shafts 13 and 16 are disposed in parallel 25 relation, the former being driven by the motor 11 and both being provided with sprockets 17 about which is trained a link-belt type chain 18. The chain 18 and the sprockets 17, as driven by the motor 11, constitute a conveying or carrying means for carrying along a linear path an element to be heat-treated. This element will be 30 later described.

A heat-treating unit generally designated by the numeral 19 is rigidly carried by the base 10 at one end thereof and at one side of the conveyer chain 18. A second heating unit, generally designated by the numeral 20, is rigidly carried by the base 10 adjacent the other end thereof and at the opposite side of the conveyer chain 19. These units are substantially identical in 35 construction and it will be understood that the detailed description of one will apply similarly to the other. The construction of one particular type of heating unit is best shown in Figures 3, 4 and 5. Each heating unit embodies a structure 40 comprising a pair of spaced vertical walls 21. These walls are welded or otherwise secured to the base or table 10, and a second pair of walls 22 spaced in a direction at right angles to the walls 21 rigidly cross-connects these walls, as 45 best shown in Figure 4. The construction is such as to provide a vertical slideway, which, since the walls are preferably of metal, is insulated by a plurality of insulating strips 23. At the lower portion of the structure and resting on the base 50 10 is rigidly disposed a metal block 24. A slide block or bearing 25 is fitted into the vertical guide-way and preferably remains stationary with respect to the structure, resting on the insulated upper portion of the block 24. A second slide 55 block or bearing 26 is slidably carried by the structure in the upper portion of the vertical guide-way and is prevented from further downward movement by an adjusting means carried by a portion 27 of one wall 21. This adjusting 60 means comprises a boss or bearing portion 28 rigidly carried by the portion 27. The boss 28 is provided with an axial bore which movably carries therein a shaft 29. This shaft extends 65 horizontally into the vertical guide-way and at its inner end is provided with an eccentric portion 30 and at its outer end with an adjusting arm or handle 31. The eccentric portion 30 engages a strip of insulation material 32 carried on the under side of the slide bearing 26.

70 Each of the walls 22 is provided at its upper

end with a vertically extending member or bolt 33. A transverse member 34 is rigidly carried by the bolts 33 and extends horizontally across and above the upper slide bearing 26. This cross member 34 operatively carries one end of a tensioning means in the form of a coil spring 35, the lower end of the spring being fitted in a cup 36 formed of insulation material disposed in a recess in the upper portion of the upper slide bearing 26. This means tends to urge the slide bearing 10 26 downwardly against the eccentric portion 30 on the rod 29 of the adjusting means.

As best shown in the sectional view in Figure 3, each of the slide bearings 25 and 26 rotatably carries a shaft 37 disposed on an axis at right 15 angles to the planes of the vertical walls 21 and also to the plane of the linear path made by the conveyer chain 18. Each shaft at its end adjacent the conveyer chain 18 carries for rotation therewith a roller 38. Each roller 38 is preferably 20 formed of copper alloy and is removably secured to a portion of the shaft 37 by a plurality of bolts 38'. The removability of the rollers is desirable from the standpoint of replacing them as they are worn from usage. Through the medium 25 of the interposition of the adjusting means for the upper slide bearing, the upper roller 38 is adjustably spaced vertically above the lower roller. It is through this space between the peripheries 30 of the rollers that the element to be heat-treated is passed.

The type of element chosen for the purposes of illustration and for which the present invention is especially adapted is a section of a knife or cutter bar of a standard mower or harvesting 35 machine. This section or element has opposite flat surfaces and is of a substantially uniform thickness, having opposite edge portions along which the cutting edges of the section are formed. It is desirable that these edges be properly heat-treated before sharpening, and, at the same time, 40 it is desirable to retain an untreated or "soft" portion in the center of the section. The disposition of this soft portion is especially important in strengthening the section, being further desirable to permit holes to be drilled therethrough 45 for the purpose of attaching the section in position on a knife. Breakage of the section is thus prevented at points adjacent the holes. The element or section will hereafter be generally designated by the numeral 39 and the opposite edge portions, angularly related, by numerals 40 and 41. It is along these edges 40 and 41 that the section must be heat-treated for providing hardened wear edges enabled to withstand continued 50 usage. It is desirable to heat-treat these portions along paths of predetermined widths.

It will be appreciated from the foregoing description that the invention, as embodied in the construction set forth, is not limited in scope to 60 its adaptation to heat-treating the specific sections defined, namely the mower or harvester knife sections, nor to the specific heating devices referred to. Any type of element having similar portions may be so treated by a similar device 65 especially adapted thereto within the scope of the invention.

In the present adaptation of the invention, the knife section 39 is carried by the conveyer chain 18 through the medium of means in the form of 70 a carrying member 42. This member 42 is movably mounted with respect to the chain 18, and, as best shown in Figures 6 and 7, a particular type of link 43 is provided for mounting the member. This link has a cross-connecting horizontal 75

portion 44, to which the carrying member 42 is pivotally carried by a pivot pin 45. This construction permits swinging movement of the carrying member with respect to the chain 18. 5 The member is formed with a holding portion or pocket 46 into which an end portion of the knife section fits, and there is no relative movement between the section and the carrying member. As best shown in Figure 1, it can be readily 10 seen that the carrying member at its forward portion is cut away and is substantially narrower than the forward portion of the knife section 39. The portions 40 and 41 of the section thereby extend beyond the sides or edges of the member 15 42, and permit passage of the portions between the rollers 38 without interference from the carrying member. The carrying member is further provided with a pair of downwardly extending spaced pins 47, which are disposed adjacent opposite sides of the link member 43. These pins provide a means for limiting movement of the carrying member with respect to the chain. From an examination of Figures 1 and 7, it will be 20 seen that these pins engage respective side portions of the conveyer chain 18 to confine swinging movement of the member 42 to movement within predetermined limits.

Starting at the left hand side of Figure 1, it will be noted that the member 42, carrying the 30 knife section 39, is moved to a position with a pin 47 engaging one side of the chain 18, so that the portion of the section along the edge 40 is disposed substantially along a line parallel to the linear path described by the conveyer chain. 35 In this position, the conveyer chain will move the knife section 39 along the linear path with the portion along the edge 40 passing between the spaced rollers 38 in the left hand heating unit 19. Current conductors 48 and 49 are connected 40 to the bearing members 25 and 26 to supply current to the rollers. Similar conductors are provided for the right hand heating unit 20. The insulating strips 23, previously described, prevent shorting of the parts in the heating unit 45 structure.

In order properly to support the carrying member and section as the section is passed between the rollers 38, there is provided a supporting or guide member 50, best shown in Figures 1 and 3. 50 The member 50 is rigidly carried by the inner wall 21 of the heating unit structure, and the carrying member is adapted to be supported on this member as it passes thereover for maintaining the proper position of the knife section 39 55 with respect to the rollers 38.

As best shown in Figures 1 and 2, a pipe 51 including a horizontal portion 52 is located in close proximity to the faces of the rollers 38 and closely at the right hand side of the vertical line 60 intersecting the centers of the rollers. The left hand end of the pipe is closed and one side of the horizontal portion 52 is formed with an elongated opening or a slot 53. This pipe provides means for supplying a quenching medium to the portion 65 of the section substantially immediately after it passes through the rollers 38. It will be noted that, when the quenching medium is continually supplied, it will be directed through the slot 53 to the section in proportion to the extent that the portion along the edge 40 is heated and leaves the rollers.

At the right hand side of Figure 1, the heating unit 20 is, as previously mentioned, disposed at the opposite side of the conveyer chain 18. 70 75 In this position, the current-conducting rollers

38 thereon are adapted to treat the opposite portion of the section along the opposite edge 41 thereof. Passage of the portion along the edge 41 between the rollers 38 of the heating unit 20 is similar to the passage along the edge 40 between the rollers 38 of the heating unit 19.

Since the edge 41 is on the opposite side of the section from the edge 40, it is desirable that means be provided for changing the position of the element with respect to the conveyer chain 18, so that the portion along the edge 41 is disposed along the linear path of the conveyer chain 18 whereby it may be treated by the rollers of the heating unit 20. For this purpose the carrying member 42, of which there may be a plurality on the chain 18, is formed with a pair of oppositely disposed cut-out or notched portions 54 and 55. To change the position of the carrying member and element from the position shown at the left hand side of the figure to that at the right hand side of the figure, an engaging member in the form of an arm 56 is secured to the inner wall 21 of the heating unit structure 20. This arm is formed with an engaging portion 57, which lies in a transverse plane at right angles to the plane of the linear path described by the chain 18. As the chain carries the carrying member and element from left to right, the engaging portion 57 of the member 56 engages the carrying member in the notch 54, as best shown in dotted lines in Figure 1. Continued linear movement of the chain from left to right moves the carrying member and element to the position shown at the right hand side of the figure. The pin 47 at that side of the member engages the respective side of the conveyer chain 18, and thus limits movement of the carrying member and element within the predetermined limits, whereat the portion along the edge 41 is disposed substantially along a path parallel to the linear path of the chain 18. A quenching medium supply means 58 is associated with the heating unit structure 20 and is similar in construction and arrangement to the quenching medium supply means for the heating unit structure 19. A similar guide or supporting means 59 is also provided and is rigidly carried by the inner wall 21 of the heating unit structure 20 for supporting the carrying member 42 for maintaining the proper position of the element with respect to the rollers 38 on that unit. 50

After opposite side portions of the section have been treated by both units, the section is permitted at the extreme right hand end of the conveyer chain 18 to drop from the carrying member into any suitable receptacle or the like. The carrying members are then carried along the lower run of the chain 18 and in order to dispose them with respect to the chain in a manner whereby the portion along the edge 40 of another section 39 may be treated, a means 60, similar to the means 56, is associated with the left hand heating unit 19 and is formed with an engaging portion 61, which engages the carrying member 42 in the notch 55, as the conveyer chain carries the member 42 along its lower run. As each carrying member 42, thus positioned, approaches at the left hand end of the chain 18, an untreated section is easily placed in the holding portion or pocket 46 and the sections are now ready to be 65 treated by the heating units 19 and 20. 70

As previously mentioned, each roller 38 has a comparatively large mass with respect to the thickness 39 and to overcome the difficulty encountered in the use of solid rollers, each roller 75

has been provided at its periphery with a plurality of current-concentrating portions in the form of axially spaced annular ribs 62. Through the provision of this means, the current is thus concentrated throughout the portions of the sections along either of the edges 40 and 41 and the intermediate portion of the section remains thus untreated or soft. The provision of the annular ribs possesses important significance in view of the fact that lack thereof would permit uneven treatment of the portions to be treated. Because of the comparative large mass of each roller, it has a tendency to become cooled and thus it cools the surface of the portion to be treated. The result would be that opposite surfaces of the portion would become prematurely cooled while an inner portion would remain hot, thus giving the cross-section of the knife section an undesirable stratified result. This undesirable result is obviated by the provision of the current-concentrating ribs 62, which insure uniform disposition of heat throughout the thickness of that portion of the knife section lying along either of the edges 40 or 41. The provision of the tensioning means including the coil spring 35 insures constant contact of the rollers 38 with the portions of the sections to be treated and also allows for any irregularities along the surface thereof. Varying thicknesses of sections are provided for by the adjusting means comprising the shaft 29, the eccentric portion 30 and the lever or handle 31.

From the foregoing description, it will be seen that one form of a desirable device has been provided, in accordance with the invention, for heat-treating one particular type of element, and that various provisions have been made for properly heating and quenching the element in accordance with the results desired to be obtained. It will be understood, of course, that various changes may be made in the device to compensate for changes in the properties and results desired from the elements to be treated. It will be still further understood that numerous other alterations and modifications may be made in the construction of the device, as illustrated, without departing from the spirit and scope of the invention as defined in the appended claims.

What is claimed is:

1. In a device for electrically heat-treating a substantially uniformly thick element having opposite surfaces along each of two angularly related portions, the combination of conveying means movable along a horizontal, linear path, a carrying member movably carried by said means and positionable with respect thereto substantially about a vertical axis, said member adapted to carry the element horizontally in either of two positions, in one position with one aforesaid portion arranged along the linear path, a pair of current-conducting rollers carried on vertically spaced horizontal axes alongside the conveying means, said conveying means moving the said portion of the element between the rollers with the peripheries of the rollers engaging respective surfaces thereof, means disposed adjacent the conveying means and spaced from the rollers, said means adapted to cooperate with the carrying member for moving same to the other of the aforesaid positions to dispose the other portion of the element along the linear path, and a second pair of current-conducting rollers carried similarly alongside the conveying means and

spaced along the linear path from the last named means for similarly treating said other portion.

2. In a device for electrically heat-treating an element having opposite surfaces along each of two angularly related portions, the combination of means movable along a linear path and including a member for carrying the element, said element being mounted on the member and positionable laterally with respect to the carrying means for disposing first one portion along said path at one side of said means and then the other portion along the path at the other side of the means, two pairs of current conducting members located at opposite sides of and spaced from each other along said means, and means disposed adjacent said linear path cooperable with the element to position same from one side of the means to the other, the carrying means passing one portion of said element between one pair of conducting members and then the other portion between the other pair of members.

3. In a device for electrically heat-treating a section of a harvester knife, in which the section is substantially triangular and has opposite surfaces along each of two sides to be treated, a carrying means movable along a linear path and including a member for carrying the section, said section being laterally positionable on the carrying means for disposing first one side of the section and then the other along the linear path at opposite sides of the carrying means, a treating means at one side of the carrying means for treating one side of the section, a second treating means spaced from the first treating means and disposed along the path at the other side of the carrying means, and means disposed intermediate the treating means for positioning the section on the carrying means to arrange the sides along the path to pass and be treated by the respective treating means.

4. In a device for heat-treating an element having angularly related portions to be treated, a flexible conveying means movable along a linear path and including a member for carrying the element, said element being carried by said member for lateral swinging movement from one side of the conveying means to another to dispose the portions of the element successively along the path, a heat-treating means at one side of the conveying means, a second heat-treating means at the other side of the conveying means and spaced along said path from the first heat-treating means, said heat-treating means being adapted respectively to treat the portions of the element, each treating means including a pair of heating rollers having their peripheries spaced substantially the thickness of the element, each means further including a guide means cooperating with the conveying means and element to guide the element between the rollers, and means positioned intermediate the treating means and cooperable with the element for swinging the element laterally on the conveying means after one portion of said element passes between the rollers of one treating means to dispose the other portion of the element along the path for passage between the rollers of the other treating means.
